AUTOMOBILE SIGNAL

Filed Jan. 17, 1928

Inventor:
C. D. Brown
By his attorney, Geo. L. Beale

UNITED STATES PATENT OFFICE.

CLARENCE DOUGLAS BROWN, OF BAYSIDE, NEW YORK.

AUTOMOBILE SIGNAL.

Application filed January 17, 1928. Serial No. 247,283.

This invention relates to automobile signal devices or indicators.

Among the objects of the invention is to provide a signal, and improved means for 5 mounting and actuating the same.

Another object of the invention is to provide a signal of the character described adapted to be projected from an automobile, as for example, a closed car, to indicate to 10 the traffic the driver's intention, and which signal is positioned in an inconspicuous manner when not in use.

A further object of this invention is the provision of a device of the character mentioned which is adapted to be mounted on the sliding window of an automobile, and which will permit unobstructed view through 15 said window, whether or not the device is in signaling position.

With the foregoing and other objects in view the invention consists in the arrangement and combination of parts hereinafter described and claimed, and while the invention is not restricted to the exact details of 20 construction disclosed or suggested herein, still for the purpose of illustrating a practical embodiment thereof reference is had to the accompanying drawings in which like reference characters designate the same parts 25 in the several views, and in which—

Figure 1 is an elevational view of a device embodying the invention and mounted in unoperated position on the window of an automobile.

Fig. 2 is a top plan view of the same and indicating in dotted lines a portion of the device in operated position.

Fig. 3 is a vertical section taken on the line 3—3 of Fig. 2, but indicating the device 40 in operated position.

Fig. 4 is a vertical section taken on the line 4—4 of Fig. 3.

Fig. 5 is a vertical transverse section taken on the line 5—5 of Fig. 2.

Fig. 6 is a fragmentary top view of a modification of the invention.

Fig. 7 is a vertical section taken on the line 7—7 of Fig. 6.

Referring now more specifically to the drawings, 10 indicates the upper portion of a closed car window adjacent to the driver's seat, such window being understood to be of that type movable up or down for closing and opening respectively. While such window in favorable weather is usually

down for purposes of ventilation and easy signaling, it of course is usually closed or ought to be closed for the comfort of the driver during wet, cold, or stormy weather, and yet the law requires that the driver project his hand from the car body and through or over this window at certain definite times for giving a signal to the other traffic.

The signal mechanism proper comprises the representation of a driver's left hand 11 of any suitable size, material, or color indication. As shown herein, however, it comprises a sheet or plate of thin material secured in or made a part of an arm 12 of suitable durable and sufficiently strong material such as bar or sheet metal. The arm 12 is always horizontal and is mounted conveniently to be swung in a horizontal plane from a position close and parallel to the upper edge of the window 10 as in Figs. 1 75 and 2, or to occupy a position at right angles thereto as in dotted lines in Fig. 2 and in full lines in Fig. 3 when the signal hand is to be displayed or brought into view with respect to persons in front or at the rear of 80 the vehicle carrying the signal.

The supporting means for the signal arm comprises a spring clamp 13 which may if desired be faced with plies of felt 14 where it is clamped or engaged over the upper 85 edge portion of the window pane 10 and where it may be carried permanently. At the top portion or crotch of the clamp is a bracket 15 which is mainly flat and lies in a horizontal plane, being connected as by 90 riveting, soldering, or otherwise to the top or crotch portion of the U-shaped clamp. The said bracket is supported at a desired distance above the top edge of the window by a rubber spacer 15' in the clamp at the 95 crotch thereof. On the inner edge or end, however, of the bracket I provide a lug or ear 16 deflected downward for the guidance of a flexible member 18 whose upper and outer end is connected to the forward or inner end 12^b of the signal arm at the point 19. The cord or other flexible member 18 leads inward and downward from the point of connection 19 through the guide member 17 which is movably carried from the bracket 17^a, and extends thence along the inner side of the window, and terminating in a finger piece or handle such as a ball 20 for convenient grasp of the driver adjacent to the wheel.

100

105

110

The bracket 15 extends outward from the clamp 13 and pivoted thereto on a vertical pivot 21 is the aforesaid arm 12. Any suitable means may be provided tending to hold 5 the signal arm inward or rearward in the position of Figs. 1 and 2 adjacent to the window 10. To this end I employ a contractile spring 22 having its ends anchored at 23 and 24 on the inner edge of the bracket 10 and on the arm respectively, the points of attachment of the spring being at the rear of the main axis or pivot 21 of the arm.

The hand 11 in unoperated position rests at 15 its outer side portion 11^a on the top of the window 10. The hand 11 is then substantially horizontal. On projection of the arm 12 the said hand has free outward sliding movement along the top edge of the window 10. Being hingedly mounted at 12^a, the hand 11 20 is free to drop into a vertical plane as shown in Fig. 4, when it has been projected sufficiently to be deprived of said window as a support. Thus at all times, both in the 25 operated and unoperated positions of the device, the window 10 is unobscured by the hand.

With the parts constructed and arranged as herein set forth, the mode of operation will be understood readily from the following résumé. It being understood that the window 10 may be approximately closed or standing in any desired position of elevation, when it is desired for the signal to be given and which would necessitate ordinarily the 30 projection of the driver's hand outward through or over the window, he simply grasps the handle 20 and draws downward on the flexible member or cord 18, causing the arm 12 to swing from the normal idle 35 position outward around an angle of approximately 90° or into such position that the signal member 11 will occupy the position practically that would be occupied by the driver's hand if he could project it in 40 the usual way. The hand simultaneously swings from a horizontal into a vertical position. This movement of the arm 12 outward is against the force of the spring 22. The pull on the cord 18 may be continued 45 as long as necessary and the hand that operates the cord may at the same time be employed on the wheel if necessary while the signal is displayed. In any event, when the signal is no longer required, the operator 50 simply releases the handle 20 and the spring 22 automatically returns the arm to its idle position where it is inconspicuous and in such position as not to disturb the driver's view at any time. The downward position 55 of the member 17 for the cord insures that the arm will have free swinging adaptability and without any danger of cutting or shearing the cord. While the device is adapted 60 for permanent attachment to the window, it 65 of course may be removed therefrom if de-

sired by simply slipping the clamp upward from the edge of the window.

In Figs. 6 and 7 is shown a modification of the arm supporting means, which differs from the construction hereinbefore described, chiefly in that the spring 22 is positioned and concealed within the clamp 13. The pivot 21 of the former device is now embodied in a screw 25. The latter is provided with a helical spring 26 between the sides of 70 the clamp and the portions 27 of the rubber spacer. One end of the said spring engages the screw in a hole 28 thereof, while the other end bears against a side 29 of the clamp. To prevent unintended turning of 75 the screw relative to arm 12, the said screw may be provided with lugs or extensions 30 which may engage in corresponding recesses in the said arm. A fastening 31 may be provided on the shank of the screw to prevent endwise movement of the same. The said fastening may be a nut threaded on the screw, or a washer pressed by the 80 said spring against the crotch portion of the clamp so as to tightly secure the member 25. 85

It will be noted that inasmuch as the hand 11 consists of a light material, such, for example, as canvas suitably reenforced, it will swing slightly in the manner of a flap about the hinge line 12^a, due to the effect of wind or vibration. This will attract a greater 90 degree of attention from the traffic, and so operate for the best purpose.

To prevent inward turning of the said hand at the instant of projection of the same, due to air resistance encountered, the lower portion of the arm 12 acts as a stop, as is clearly shown in Fig. 4.

I claim:

An automobile signal of the character described, including a clamp for engaging the upper edge portion of a vertically movable window panel of the automobile, vertical pivot carried by the clamp, an arm mounted on said pivot to move over the upper edge of 105 the panel, means to swing the arm into outward extending relation with respect to the said panel, and a signal member made of a stiff material directly connected to said arm and depending therefrom, said signal member having a weakened line forming a hinge line in and integral with the signal member, the signal member depending from said arm in the last mentioned position thereof in 110 a substantially vertical plane, said signal member having wiping contact with the top edge portion of the panel on inward movement of said arm to cause the signal member to swing about its hinge line into a substantially horizontal plane above the upper edge 115 of the panel, the signal member resting on the upper edge of the panel, in any position 120 of elevation of the panel.

In testimony whereof I affix my signature.

CLARENCE DOUGLAS BROWN.
